J. M. CRAIG

GAS ENGINE CONTROL DEVICE

Filed April 24, 1925

FIG. 2.

FIG. 3.

JOHN M CRAIG
INVENTOR

BY Clinton B. Brock

ATTORNEY

UNITED STATES PATENT OFFICE.

JOHN M. CRAIG, OF OGDEN, UTAH.

GAS-ENGINE-CONTROL DEVICE.

Application filed April 24, 1925. Serial No. 25,689.

The control device involves the use of fluid pressure mechanism in connection with an electrical circuit maker for controlling the ignition circuit of an internal combustion engine, especially adapted for use on automotive vehicles.

My invention contemplates mechanism actuated under influence of fluid pressure, as for instance from the exhaust gases of the 10 internal combustion engine, for electrically cutting out or suspending the operation of the ignition system of the engine or motor when a predetermined maximum speed has been attained by the motor or engine. 15 Means are provided whereby the control device may be adjusted or set to vary the predetermined maximum speed at which the mechanism becomes operative to suspend the ignition, and the mechanism is adapted to 20 automatically restore the ignition system to operative condition when the excessive speed has been reduced to the predetermined maximum.

The invention consists in certain novel 25 combinations and arrangements of parts as will hereinafter be more fully set forth and claimed.

In the accompanying drawings I have illustrated one complete example of the 30 physical embodiment of my invention wherein the parts are combined and arranged in connection with the exhaust manifold of an internal combustion engine and according to one mode so far devised and successfully 35 operated according to the principles of my invention. It will be understood that other means may be utilized to supply the fluid pressure to the control device and changes and alterations may be made therein within 40 the scope of my claims without departing from the spirit of my invention.

Figure 1 is a view in side elevation, partly broken away for convenience of illustration showing the device of my invention connected with a portion of the exhaust manifold of an internal combustion engine.

Figure 2 is a vertical sectional view at line 2-2 of Figure 1.

Figure 3 is a diagrammatic view showing 50 the electrical wiring of the device in combination with the ignition system of an internal combustion engine.

In the present exemplification of my invention the device is shown connected with the 55 wall 1 of the exhaust manifold of an internal

combustion engine in such manner as to receive exhaust gases from the engine or motor for the operation of the device.

For this purpose I utilize a nipple 2 threaded into the wall 1 of the exhaust manifold and a regulating, manually operated, valve device, indicated as a whole by the numeral 3 is connected to the nipple.

At the other side of the regulating valve-device I employ a coupling 4 and an elbow 5 in which a bushing 6 is threaded, and on the bushing a tubular structure or pipe 7 is threaded, to form a pressure chamber in communication with the exhaust manifold and adapted to receive fluid pressure therefrom.

The tubular structure or pipe 7 performs the functions of a cylinder and these parts are threaded together and are fashioned in suitable lengths and of proper dimensions and shapes to maintain the cylinder as an upright pressure chamber in which a buoyant float device 8 is supported in normal position on the annular shoulder 9 formed by the top edge of the bushing 6.

The float, which is fashioned in suitable manner, is designed to perform the functions of a movable contact member for a circuit maker and breaker, and for this purpose is provided with a metallic conducting cap 10 affixed therein in approved mode. The stationary contact members of the circuit maker and breaker are carried in the upper end of the cylinder 7 in the upper open end of which is threaded a bushing 90 11 in which is fixed a holder or block 12 of insulating material or non-conducting material and provided with a vent opening 12' extending from the interior of the pressure chamber of the cylinder to the atmosphere. 95

The conductor-cap 10 of the float is designed to co-act with a pair of spaced stationary contact points 13 and 14 for completing an electric circuit that will pass through these members when they are in 100 contact.

Under influence of the exhaust gas pressure from the manifold 1 and the intervening members of the control device, the float 8 will be lifted to cause contact between 105 the members 10 and 13 and 14 to close the normally open control circuit of the control device, which includes terminals 15 and 16.

The passage of gas through the valve de- 110

vice 3 is regulated by means of a manually operated valve head 17 which is adapted to regulate the opening of the complementary valve seat 18 which is fashioned with a normally open by-pass or duct 19 for the exhaust gases to pass through from the exhaust manifold.

In the diagrammatic Figure 3 I have shown an example of the application of my invention to the ignition system of an internal combustion engine which includes a coil 20 and a distributor 21 for the four spark plugs indicated at 22 used in connection with the engine cylinders, the ignition circuit being indicated by the numeral 23.

For the electric circuit of the control device I employ a low tension wire 24 connected to the coil 20 and to the battery 26 and the wire is grounded at 27 to the rear portion of the engine or to the frame of the automotive vehicle in suitable manner. The control device is connected with the ignition system or circuit by wire 28 from the terminal 16, and the wire 29 from the terminal 15 is grounded on the engine, as indicated in Figure 3.

In operation when the valve 17 is set to permit flow of a predetermined pressure of exhaust gases to the chamber 7, and the exhaust gases reach such a pressure, the float and its contact head 10 are lifted to cause contact between the head and the stationary heads 13 and 14 of the terminals 15 and 16. An electrical connection is thus established which short-circuits or cuts out the ignition circuit 23 as indicated in Figure 3 for the purpose of suspending ignition on the part of the spark plugs in the ignition circuit. This suspension occurs when the engine or motor reaches a speed corresponding to the maximum speed predetermined by the adjustment of regulation of the valve 17. The lowering of the speed of the engine following suspension of ignition results in a reduction of the pressure in the pressure chamber and consequent fall by gravity of the float 8 to break the control circuit and

restore the ignition circuit to operative condition.

To prevent the automotive vehicle driver from entirely closing the outlet from the exhaust manifold through the regulating device I utilize the by-pass or duct 19 of the valve which is constantly open to permit a certain amount of fluid pressure in the chamber 7 at a given rate of speed of the engine.

It will be apparent that by increasing the opening of the regulating valve 17 to permit passage of increased volume and pressure of gases through the control device, the slower will be the resulting speed of the engine, and that by reducing the opening of the valve 17, the greater will be the speed possible of attainment by the engine.

The valve may be adjusted to suit various speeds of the engine but should be only within a range that is below the maximum speed permitted by traffic regulations. The driver may thus adjust the valve 17 from the maximum speed allowed on highways to the lesser speeds permitted in cities.

While I have shown a manually operated regulating valve 17 it will be understood that the valve may automatically be operated by connection with a speedometer or other accessory of the automotive vehicle suitable for the purpose.

Having thus fully described my invention, what I claim as new and desire to secure by Letters Patent is—

The combination with an internal combustion engine having an exhaust manifold and an electric ignition system, of a manually adjustable valve connected with said manifold and a pressure cylinder connected with said valve, a head in the cylinder having spaced stationary contact points, a float in the cylinder having a complementary contact point, and electrical connections whereby the electric ignition system is short-circuited when said points are in contact and the ignition system restored when said points are subsequently disengaged.

JOHN M. CRAIG.
